UNITED STATES PATENT OFFICE.

CYRUS V. OSBORN, OF DAYTON, OHIO.

OVERALLS.

SPECIFICATION forming part of Letters Patent No. 354,928, dated December 28, 1886.

Application filed November 5, 1886. Serial No. 218,028. (No model.)

To all whom it may concern:

Be it known that I, CYRUS V. OSBORN, a citizen of the United States, residing at Dayton, in the county of Montgomery and State of Ohio, have invented a certain new and useful Improvement in Overalls; and I do hereby declare that the following is a full, clear, and exact description of the invention, which will enable others skilled in the art to which it appertains to make and use the same, reference being had to the accompanying drawings, and to the letters of reference marked thereon, which form a part of this specification.

My invention relates to improvements in overalls; and it consists in a flap extending across the front and pocket-openings in the band parallel to the side oblique edges of the said flap.

The object of my invention is to simplify the construction of the overalls by substituting a flap for the usual central opening, and so arranging the pockets that they are accessible without interference or contact with the flap.

I attain the object by the construction illustrated in the accompanying drawing, in which the figure is a front view of the overalls with a portion of the flap cut away.

In general construction the overalls are manufactured as usual for such garments, the difference chiefly consisting in the use of a flap instead of the usual central opening.

F F are the legs of the garment, and the outline of the back is shown at E.

A constitutes the front of the body of the garment, or the band, which is of two symmetrical parts united by buttons at the center.

The pockets B B are attached to these parts, and the oblique openings to which are shown at C C.

D is the flap of the garment and extends across the front from one side seam to the other, the corners being cut obliquely and parallel to the pocket-openings. It is held to the band by buttons on said band. When freed from the buttons, the flap falls down, as indicated by dotted lines.

Having fully described my invention, what I claim, and desire to secure by Letters Patent, is—

A pair of overalls provided with waistband A, united at the center, with oblique pocket-openings C C in said band, and flap D, with corners cut parallel to said pocket-openings, substantially as set forth.

In testimony that I claim the foregoing as my own I affix my signature in presence of two witnesses.

CYRUS V. OSBORN.
